UNITED STATES PATENT OFFICE

PAUL M. HASSSLER, OF FAIRFIELD, IOWA, ASSIGNOR TO THE LOUDEN MACHINERY COMPANY, OF FAIRFIELD, IOWA, A CORPORATION OF IOWA

STOP FOR OVERHEAD CARRYING EQUIPMENT

Application filed April 19, 1928. Serial No. 271,122.

My invention relates to stops for use with overhead carrying equipment wherein a trolley is adapted to run on an overhead trackway, a section of the trackway being arranged to be raised and lowered to either align with the stationary portion or portions of the trackway, or to be disconnected therefrom. A number of overhead trackways may be used, one above the other, such as may be necessary in a building having a number of stories with a stationary trackway in each story, and the movable portion of the trackway is to be raised and lowered to align with either of the stationary trackways in the different stories, or to be disconnected therefrom, as may be required to transfer the trolley or trolleys from any one of said stationary trackways to any other.

The principal object of my invention is to provide an improved form of stops to prevent the trolley or trolleys from running off the ends of the trackways when out of alignment with a co-operating portion, and to also permit said trolley or trolleys to pass freely over the co-operating portions of said trackways when said portions are in proper alignment with each other, the operations of said stop devices being automatic and simultaneous, as the movable portion of the trackway is elevated or lowered from one position to another and into alignment with stationary sections of trackways. My improvement also consists of novel details of construction which will be herein described and definitely set forth in the claims.

In the accompanying drawings, forming a part of this specification, Fig. 1 is a side elevation, partly in vertical section, of a portion of an overhead carrying equipment embodying my invention, which will be more fully explained hereafter. Fig. 2 is a horizontal section on line 2—2 of Fig. 1; looking in the direction of the arrows, the parts cut away in Fig. 1 being replaced to make the structure complete. Fig. 3 is an enlarged plan view of the operating portions of the stop devices, a portion of the movable and the stationary trackways being shown in alignment with each other, and the stops being swung up to one side to permit the trolley to pass from

one portion of the trackway to the other, said stop devices always being used in pairs, one for each end of the co-operating portions of the trackways and their mechanism operating each other.

Fig. 4 is an enlarged perspective of one of the stop devices and their mechanism connected to a trackway, and being in position to prevent the trolley from running off the end of the trackway. Fig. 5 is the same showing the stop raised to one side to permit the trolley to pass on to a co-operating trackway which is not shown. Fig. 6 is an end view of Fig. 4, or in other words, a view looking directly at the near end of the trackway with the stop mechanism attached. Fig. 7 is a detail view which will be hereafter explained.

Referring to the drawings, No. 10 represents the movable portion of the trackway which is preferably connected to the support 11 by a series of hangers 12. In order that said movable track section may be disconnected from the stationary sections 13, and be raised and lowered to align with other track sections above or below, such as 14 shown above in Fig. 1, it is preferable that a frame composed of side members 15 and end members 16 be provided, to which frame the supporting member 11 may be connected, as most plainly shown in Fig. 2. Furthermore, to hold this frame in place in its movements up and down, vertically disposed members 17 may be used.

It is preferable to have four of these members 17, one at each corner of the frame carrying the supporting member 11 with the track section 10. These guide members, as they may be called, may be connected to beams in each of the floors in the building in which they are used, or they may be otherwise supported, and there must be an open space between them from the top to the bottom for the passage up and down of the frame carrying the track section 10. Also, additional guiding members 18 may be applied to the inner sides of the members 17, and co-operating guiding members 19 may be attached to the corners of the frame 15 and 16 for the track section 10 to co-operate with

the members 18, as most plainly shown in Fig. 2. It is furthermore preferable that the members 11 and 19 be made of channel iron. The frame carrying the track section 10 may be raised and lowered in any suitable manner, such as by cables 20 attached by clips to the supporting member 11, as shown, or otherwise, and then be connected at their upper ends to suitable hoisting and lowering mechanism.

The different stationary track sections, 13 and 14, and as many others as may be used in the different stories of the building, may be supported in any suitable manner, like the supports of the movable track section 10 to the member 11, or otherwise, but at the ends of the track section 10, and also on the ends of all the other co-operating track sections, it is preferable to have special hangers 21, which, besides effectually gripping and holding the trackway, will also be adapted to be suitably connected to the members 22 which carry the stops 23 and also the mechanism for operating them. As before stated, these stops always operate in pairs and with each other, so as to prevent the trolleys from running off the ends of the co-operating trackways when not in alignment, and each member 22, besides carrying a stop 23 and the mechanism for operating it, is also provided with means for simultaneously operating the stop mechanism on the adjacent member 22, for which purpose these members are placed in reverse position, as shown in Fig. 3.

As will be seen most plainly in Figure 3, the stop members 23, which are shown in open position, have their inner ends rigidly secured to the outer ends of shafts 24 which are shown in Figs. 4, 5 and 6, but not in Figure 3, said shafts are each journaled in a central portion of the members 22 and at approximately right angles thereto. On the opposite or meeting ends of each of the shafts 24, partial cog gears 25 are mounted, or in other words, castings which have semi-circular portions with gears part way around. These gears are meshed in similar adjacent gears 26 which are formed on members 27, and are provided with long cog portions 28 to limit the revolutions of the co-acting cogs. The members 27 are journaled on cylindrical portions 29 of the members 22, and are provided with outstanding portions 30 which, when the track sections are in alignment, are adapted to come into contact with the outstanding portions 31 of the opposite member 22. The co-operating mechanism of the track sections being reversed to co-operate, some of the parts are below and cannot be shown in Figure 3.

The upper and lower ends of the outstanding portions 31 are beveled, as shown in Figs. 4, 5, 6 and 7, and when the co-operating track sections are brought into alignment by the movement of the track section 10 from either

below or above, the outstanding opposite portions 30 of the members 27 will be brought into contact with the bevel edges of the portions 31 and will be pushed either up or down according to the up or down movement of the track section 10. This will cause the member 27 to rotate to a certain extent in the same direction, and the cogs 26 on the members 27, being in mesh with the cogs 25, will cause them and the shafts 24 to which they are fixed to also be rotated, and the stops 23 will be simultaneously swung to the side, as shown in Fig. 3, thus clearing the trackway for the passage of the trolleys.

When the movable track section 10 is below and is moved upward, the upper edges of the parts 31 which it carries, coming in contact with the parts 30 on the other sections, will move these parts 30 upward, which will cause the co-operating gears 25 and 26 (see Fig. 6), to rotate, and this will rotate the shafts 24 carrying the stops 23 on the stationary sections 13, and will cause them to be swung to the side, as shown in Figs. 1 and 3. At the same time and simultaneously, the parts 30 on the movable section, coming in contact with the under sides of the parts 31 on the stationary sections, will be pushed downward, and this will cause the co-operating gears 25 and 26 to rotate, which will also rotate the shafts which carry the stops 23 on the movable section, which stops will be simultaneously swung to the side, as also shown in Figs. 1 and 3. When the movable section is above and is lowered into alignment with the stationary sections, all the movements will be reversed, and the stops 23 will be swung to the opposite side of the trackway, as shown in Fig. 5.

As shown by Fig. 7, which is a perspective of one of the members 22, a lower central portion of the member is extended downward to form the opening 32 in which the shaft 24 is journaled. As this shaft is horizontally disposed and is mounted above and in line with the track section, and also above the hanger 21 connected to it, the upper end of the hanger connected to the member 22 is preferably spread apart, and the upper ends of the hanger, which is preferably made of two parts, which are made to straddle the downwardly extended portion having the opening 32 and said upper ends are extended laterally to receive the bolts 33 by which the hanger 21 is connected to the member 22. It is also important that the hanger 21 be securely attached to the track section because it is close to the stop 23, the lower end of which may be bumped against severely. It is therefore preferable to use two or three bolts 34, in connecting the hanger to the track section, as shown in Figs. 4, 5 and 6.

In the drawings, 35 represents trolleys and 36 the beams in the building to which the trackways carrying the stop devices are con-

nected. The portions 30 are preferably made hollow to save metal. The invention is extremely simple, easily constructed and installed, and is effective in operation.

Applicant considers the shafts 24 on which the stops 23 are mounted, and the co-operating gears 25 thereon, as the preferable form of his stop mechanism, but the fundamental improvement is the construction of co-operating stop mechanisms with outstanding portions which, when in alignment, will come in contact with each other, and, of themselves alone, will cause the co-operating stops to be simultaneously moved out of the line of travel of the trolley on the trackways, and, when not in alignment, will permit said stops to be automatically and simultaneously moved into said line of travel, to prevent the trolley from running off the open end of the trackway. Any co-operating mechanism of the stop devices that, of itself alone, and without the aid of other parts, will simultaneously cause this result, will be within the scope of the invention.

What I claim as new and desire to secure by Letters Patent is:

1. In a device of the character described, having cooperating track sections and a trolley to run thereon, a supporting member mounted on each of the adjacent ends of the track sections, a pair of stop devices, each rigidly connected at one end to a shaft journaled in each of the supporting members, the other ends of the stop devices being adapted to hang down and prevent the trolley from running off the end of the track section on which it is mounted when not in alignment with the other section, and means to turn both of said shafts and thus lift the free ends of the stop devices up out of the way of the trolley when the track sections are in alignment with each other.

2. In a device of the character described, having cooperating track sections and a trolley to run thereon, a supporting member mounted on each of the adjacent ends of the track sections, a pair of stop devices each rigidly connected at one end to a shaft journaled in each of the supporting members, the other ends of the stop devices being adapted to hang down and prevent the trolley from running off the end of the track on which it is mounted when not in alignment with the other section, a gear on the opposite end of each shaft, and means on each of the supporting members to operate the gear and thus turn the shaft on the opposite member when they are in alignment with each other, whereby the stop devices will be lifted out of the way of a trolley on either track section which will then be free to run onto the other section when they are in alignment with each other.

3. In a device of the character described, having cooperating track sections and a

trolley to run thereon, a supporting member mounted on each of the adjacent ends of the track sections, a pair of stop devices each rigidly connected at one end to a shaft journaled in each of the supporting members, the other ends of the stop devices being adapted to hang down and prevent the trolley from running off the end of the track section on which it is mounted when not in alignment with the other section, a gear on the opposite end of each shaft, a cooperating gear mechanism mounted on each of the supporting members and means to operate said gear mechanism whereby the shafts carrying the stop devices will be turned, and the stops will be lifted out of the way, and a trolley on either track section will be free to run onto the other section when they are in alignment with each other.

4. In a device of the character described, having cooperating track sections, one of them being movable upward and downward and the others being stationary, and a trolley to run thereon, a supporting member mounted above the adjacent ends of each of the track sections and at substantially right angles thereto, a shaft journaled in each of the supporting members substantially in line with the track sections and with its ends extending out on each side of the supporting member, a stop device having one end rigidly affixed to the inner end of each shaft, the other end of the stops being adapted to hang down over the track section and prevent a trolley from running thereby when the track sections are not in alignment, and means to cause the shafts to revolve and turn the lower ends of the stops to one side or the other, and out of the way of the trolley when the track sections are in alignment with each other.

5. In a device of the character described having track sections, a trolley to run thereon, supporting members, shafts journaled therein, and stop devices affixed to said shafts, all arranged and operating substantially as described, in combination with a gear on the opposite ends of the shafts, cooperating gear members pivoted on said supporting members, an outstanding portion on each of the cooperating gear members and an outstanding portion on each of the supporting members, said outstanding portions being so arranged that when the track sections are in alignment with each other, the outstanding portion on each supporting member will come in contact with the outstanding portion on the cooperating gear member pivoted on the other supporting member, which will cause the shafts to revolve in one direction or the other, and will thereby lift the stop devices out of the way of the trolley in running over the track sections.

6. In a device of the character described having track sections, a trolley to run thereon, supporting members, shafts journaled

therein, and stop devices affixed to said shafts, all arranged and operating substantially as described, in combination with a gear on the opposite ends of the shafts, cooperating gear members pivoted on said supporting members, an outstanding portion on each of the supporting members, said outstanding portions being so arranged that when the track sections are in alignment with each other, 10 the outstanding portion on each supporting member will come in contact with the outstanding portion on the cooperating gear member pivoted on the other supporting member, which will cause the shafts to revolve in one direction or the other, and will thereby lift the stop devices out of the way of the trolley in running over the track sections, one or the other of the gears being provided with extended cogs to act as stop devices to 20 limit the revolution of the shaft.

7. In a device of the character described having track sections, a trolley to run thereon, supporting members, shafts journaled therein, and stop devices affixed to said shafts, 25 all arranged and operating substantially as described, in combination with a gear on the opposite ends of the shafts, cooperating gear members pivoted on said supporting members, an outstanding portion on each of the 30 cooperating gear members and an outstanding portion on each of the supporting members, said outstanding portions being so arranged that when the track sections are in alignment with each other, the outstanding 35 portions on each supporting member will come in contact with the outstanding portion on the cooperating gear member pivoted on the other supporting member, which will cause the shafts to revolve in one direction or 40 the other, and will thereby lift the stop devices out of the way of the trolley in running over the track sections, the outstanding portions of the cooperating cog members being cylindrical, and the upper and lower edges 45 of the co-acting portions of the supporting members being beveled to come in contact with and operate the cooperating cog members.

8. In an overhead carrying equipment having a trolley to run on overhead trackways, a horizontally disposed track section adapted to be vertically raised and lowered to different elevations in a building, and to be brought into alignment with stationary trackways 55 in said different elevations, whereby the trolley may be transferred from and to any of the trackways; stop devices being mounted on the adjacent ends of the trackways and arranged to permit the transfer of the trolley 60 from one trackway to another when in alignment therewith, and to prevent the trolley from running off the end of a trackway when not in alignment with another, and the mechanism of said stop devices being alike, and 65 being provided with outstanding portions

which will come in contact with each other when the trackways upon which they are mounted will be in alignment, and the contact of said outstanding portions, of themselves and without the aid of other parts, will simultaneously move the stop devices out of the way of the trolley and will permit it to be transferred from one of the trackways to the other.

Fairfield, Iowa, April 17, 1928.
